UNITED STATES PATENT OFFICE.

EDWARD KIRBY BOTTLE, OF NIAGARA FALLS, NEW YORK, ASSIGNOR TO THE CARTER-CRUME COMPANY, LIMITED, OF NIAGARA FALLS, NEW YORK, A CORPORATION.

MANIFOLDING SALES-BOOK.

1,024,496.

Specification of Letters Patent. Patented Apr. 30, 1912.

Application filed May 16, 1911. Serial No. 627,490.

To all whom it may concern:

Be it known that I, EDWARD KIRBY BOTTLE, a citizen of the United States, residing at Niagara Falls, in the county of Niagara and State of New York, have invented certain new and useful Improvements in Manifolding Sales-Books, of which the following is a full, clear, and exact description, such as will enable others skilled in the art 10 to which it appertains to make and use the same.

This invention relates to sales books, and with regard to the more specific features thereof, to manifolding sales books adapted 15 to be used by clerks in stores.

One of the objects of the present invention is to provide a simple and practical form of sales book which will be convenient to handle.

20 Another object is to provide a manifolding sales book using continuous fold sheets with means whereby the record of the sales made may be accurately kept in the book.

Another object is to provide practical and 25 efficient means for checking up the sales made by each clerk.

Other objects will be in part obvious and in part pointed out hereinafter.

The invention accordingly consists in the 30 features of construction, combinations of elements and arrangement of parts which will be exemplified in the construction hereinafter set forth, and the scope of the application of which will be indicated in the 35 following claims.

In the accompanying drawing, wherein 40 is shown two of various possible modifications, Figure 1 is a perspective view showing one form of book; Fig. 2 is a longitudinal sectional view thereof; and Fig. 3 is a modification showing a book opening at 45 the side instead of the end.

Similar reference characters refer to similar parts throughout the several views of 50 the drawing.

Referring to the drawing in detail, and more particularly to Fig. 1, a support 1 is 55 flexibly connected with a cover 2 by means of a hinge 3. At its opposite end is similarly connected a backing 4 by means of a flexible hinge 5. The opposite end of the backing 4 is provided with holes or cut away portions 6 through which are adapted to pass filing pins 7 upon the support 1.

Mounted upon the backing 4 is a removable 55 pad, comprising a plurality of duplicate and original sheets 8 and 9, respectively. As herein shown and described, this pad is of that style generally known as "continuous fold" or zig-zag as more clearly 60 shown in Fig. 2. Manifolding material, such as carbon sheet, 10, is associated therewith in order that the record may be made in duplicate. It is, however, to be understood that the carbon sheet may be omitted 65 and the back of the original sheet carbonized if so desired.

The end of the backing 4 opposite its hinged connection 5 is preferably cut away at 11 in order that the duplicate sheets may 70 be held in position on the under side of the backing when the device is opened, or until the edge of the sheet is perforated by the pins 7 on closing the device. There is also provided upon the support 1 a plurality 75 of holding pins 12 engaging suitable recesses or cut away portions 13 in the backing 4. These pins 12 are adapted to be engaged by one end of the duplicate sheet and hold the same in proper relative position upon the support 1 until forced down 80 upon the filing pins 7 by the backing 4 as above described.

The duplicate sheet as shown in Fig. 1 is divided into two parts denoted by the 85 numerals 8 and 14, separated by a line of perforations 15 in order that the same may be conveniently separated. The shorter of these two parts, that is 14, may be kept by the clerk as a voucher for the sale made, 90 and filed upon the filing pins between the support and backing in substantially the manner above described, the part 8 being sent to the cashier with the amount received, while the original sheet 9 is delivered to the 95 customer with the goods purchased.

When using this system of recording sales, a short turned up flange 16, Fig. 2, is secured to the under side of the backing to engage and hold the edge of slip or 100 voucher 14 until the same is forced down upon the filing pins by the closing of the book. The various parts of the duplicate and original leaves are similarly consecutively numbered, as indicated by the numeral 171, in order that the records of any particular transaction may be conveniently found. The cover 2 is provided with a 105

pocket 17 (Fig. 1) into which the edges of the detached levers may be temporarily placed.

After entirely using one pad the vouchers 5 may be removed from the filing pins and bound together by a rubber band, or binding 10 clips, and retained by the clerk.

Referring to Fig. 3, the construction is substantially the same as that above described, only in this case the backing 4 is hinged along one side of the support, and the cover 2, with pocket 17, at the opposite side thereof. The pins 12 are positioned at the lower end of the support in a similar 15 manner, and engage the holes of the cut away portions 13 in the back. Instead of having the holding flange for the sales vouchers positioned transversely on the rear of the backing it is more convenient to place 20 the same along one edge, for as the book is held in the left hand and opened substantially as shown in Fig. 3 the voucher may be more conveniently slipped into position until forced upon the filing pins on the closing 25 of the book.

The operation and manner of use of a device of this character is substantially as follows: A record of the sales is made upon the original sheet in a well known manner, and 30 the same is recorded upon the duplicate sheet through the manifolding means. The original and duplicate sheets are then torn from the pad, the original sheet being delivered to the customer with the goods purchased, while the duplicate sheet is retained 35 by the clerk, who swings the backing away from the support and places the sheet with its lower edge resting upon the pins 12. On closing the device the sheet is forced 40 down upon the pins which perforate the sheet and hold the same against removal when the backing is again swung away to receive the duplicate record of the next transaction. If the sheets are of that style shown 45 in Fig. 1 the duplicate sheet is separated into its two parts, one part being sent to the cashier while the other part is filed in the back of the book in substantially the manner above described. It is to be noted that 50 the pins 7 are slightly inclined toward the holding pins whereby as the sheets are forced down upon the filing pin the lower edge will be moved away from the holding pins 12, thereby positively preventing a 55 buckling of the duplicate sheets as they are filed, and also leave the holding pins free to receive the edge of the duplicate sheet at all times.

It is thus seen that this invention provides 60 a simple and practical means of retaining a record of all transactions made by any individual clerk, and also a record in the sales book when using the continuous fold pads.

The device is simple to construct and 65 cheap to manufacture and all its parts are

positioned and arranged so as to permit the same to be easily and quickly handled by the clerks, thereby accomplishing, among others, the objects and advantages above set forth.

As many changes could be made in the above construction and many apparently widely different embodiments of this invention could be made without departing from the scope thereof, it is intended that all matter 70 contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention, which, as a matter of language, 75 might be said to fall therebetween.

Having described my invention, what I 80 claim as new and desire to secure by Letters Patent is:

1. In a device of the character described, in combination, a pair of hinged members, 90 a pad directly associated with one of said members, and a filing pin permanently connected with one of said members and positioned thereon to perforate and hold sheets of said pad after being torn therefrom and 95 placed between said hinged members.

2. In a device of the character described, in combination, a pair of flexibly connected members, a pad associated with one of said members, and a pin permanently secured to 100 the other of said members adapted to perforate and hold the leaves of said pad when detached therefrom and placed between said members.

3. In a device of the character described, 105 in combination, a support, a backing flexibly secured to one edge thereof, a pad positioned upon said backing, and a plurality of pins mounted upon said support adapted to hold some of the sheets in position between 110 the support and said backing after being removed from said pad.

4. In a device of the character described, in combination, a support, a backing secured to one edge thereof, a pad positioned upon 115 said backing, and a plurality of inclined pins mounted upon one of said first mentioned parts, adapted to perforate and hold some of the sheets of said pad after being removed therefrom and placed intermediate said support and said backing.

5. In a device of the character described, in combination, a support, a backing flexibly secured to one edge thereof, a pad positioned upon 125 said backing, a plurality of pins mounted upon one of said first mentioned parts, inclined toward said flexible connection and adapted to perforate and hold some of the sheets of said pad after being removed therefrom and placed intermediate 130

- said support and said backing, and means secured to the other of said first mentioned parts for holding a detached sheet in position thereon until the same is perforated by 5 said pins on closing the device.
6. In a device of the character described, in combination, a support, a pin near one end of said support, a backing flexibly secured to the other end thereof, and a pad of 10 continuous original and duplicate leaves mounted upon said backing, said backing having a cut-away portion at the end opposite its flexible connection whereby a leaf after being detached from said pad may be 15 held by the operator in proper relative position until perforated by said pin upon closing the device.
7. In a device of the character described, in combination, a support, a plurality of inclined pins near one end of said support, a backing flexibly secured to the other end thereof, and a pad of continuous original and duplicate leaves mounted upon said backing, said backing having a cut-away 20 portion at the end opposite its flexible connection whereby a leaf after being detached from said pad may be held by the operator in proper relative position until perforated by said pins upon closing the device.
8. In a device of the character described, in combination, a support, a filing pin near one end thereof, a backing hinged at the opposite end having a cut-away portion through which said filing pin may pass, a 25 pin mounted upon one of said members near the hinged connection engaging a recess in the other member, and a pad mounted upon said backing, the sheets of said pad being adapted to be torn therefrom and placed between said support and said backing and held in proper relative position by said second mentioned pin until perforated by the 30 filing pin.
9. In a device of the character described, in combination, a support and a backing hinged at one end thereof, a filing pin and holding pin positioned at opposite ends on one of said members engaging cut-away portions in the other of said members, a pad of 35 continuous sheets mounted upon said backing, and manifolding means associated therewith whereby the record may be made in duplicate, the duplicate sheets adapted to be torn from said pad and placed intermediate the backing and support and held in proper relative position by the holding pin until perforated by the filing pin.
10. In a device of the character described, in combination, a support, a backing hinged 40 upon one end thereof, holding pins and filing pins mounted upon one of said members near the opposite ends thereof engaging cut-away portions in the other of said members,
- a pad of continuous sheets forming duplicate and original sheets mounted upon said backing, one of said sheets being perforated intermediate its ends, manifolding means associated therewith, said sheets adapted to be torn from said pad and separated into parts, and a temporary holding means upon the under side of said backing adapted to receive one of the parts of said separated sheet and to hold the same in proper relative position until perforated by the filing pin. 45
11. In a device of the character described, in combination, a support, a backing hinged upon one end thereof, holding pins and filing pins mounted upon one of said members near the opposite ends thereof engaging cut-away portions in the other of said members, a pad of continuous leaves forming duplicate and original sheets mounted upon said backing, one of said sheets being perforated intermediate its ends, manifolding means associated therewith, said sheets adapted to be torn from said pad and separated into parts, temporary holding means upon the under side of said backing adapted to receive one of the parts of said separated sheet and to hold the same in proper relative position until perforated by the filing pin. 50
12. In a device of the character described, in combination, a support, a backing flexibly hinged to one side thereof, filing pins mounted upon said support engaging cut away portions in said backing, and a pad of continuous sheets mounted on said backing having a cut away portion at the end thereof adjacent said filing pins whereby the sheets when torn from said pad may be placed upon the under side of said backing and held by the operator through said cut away portion until engaged by the filing pins. 55
13. In a device of the character described, in combination, a support, a backing flexibly hinged to one side thereof, filing pins mounted upon said support engaging cut away portions in said backing, a pad of continuous sheets mounted on said backing having a cut away portion at the end thereof adjacent said filing pins whereby the sheets when torn from said pad may be placed upon the under side of said backing and held by the operator through said cut away portion until engaged by the filing pins, and a cover for said device flexibly secured to the opposite side of said support. 60

In testimony whereof I affix my signature, in the presence of two witnesses.

EDWARD KIRBY BOTTLE.
